UNITED STATES PATENT OFFICE.

JOHN C. WENNER, OF SUMMIT, ILLINOIS.

WEEDER.

No. 896,494.

Specification of Letters Patent.

Patented Aug. 18, 1908.

Application filed February 27, 1908. Serial No. 418,034.

To all whom it may concern:

Be it known that I, JOHN C. WENNER, a citizen of the United States, residing at Summit, county of Cook, and State of Illinois, have invented certain new and useful Improvements in Weeders, of which the following is a specification.

My invention relates to weeders and particularly to hand weeders for garden use.

10 The object of my invention is to provide a small hand weeder which shall be of simple construction, easy to use and of low cost to manufacture.

15 A further object of my invention is to provide a weeder so constructed and arranged that the cutting edge may be changed from a straight to a curved one or vice versa as desired.

Other objects will appear hereinafter.

20 My invention will be more readily understood by reference to the accompanying drawings forming a part of this specification, and in which,

25 Figure 1 is a perspective view of a weeder embodying my invention in its preferred form, Fig. 2 is an elevation thereof in the position it assumes when presenting a curved cutting edge, and Fig. 3 is a detail cross section of the blade upon an enlarged scale.

30 The weeder embodying my invention is formed of a single strip of flexible or elastic metal suitably bent, the central portion being arranged and sharpened to constitute a blade and the ends being arranged parallel to 35 form a grip or handle at right angles to the blade portion. The parallel portions of the handle normally stand a slight distance apart at which time the blade portion is perfectly straight, and the device has sufficient rigidity 40 to permit it to be readily used in this position.

45 By tightening the grasp on the handle portion said portions are drawn together and the blade portion is consequently curved.

Referring to the drawings 1 indicates an 45 elastic strip of metal which is bent to form a

horizontal portion 2, the vertical riser portions 3 extending at right angles from the portion 2 the inwardly extending portions 4 and the parallel end portions 5 which constitute the handle. The portion 2 constitutes 50 the blade and both edges thereof are sharpened preferably upon its lower face as indicated at 6, and from end to end thereof. The portions 4 are in alinement with each other and parallel with the portion 2 and their 55 combined lengths are less than that of the blade, hence the handle portions 5 are normally held a short distance apart, said handle portions being at right angles to the portion 4. When it is desired, for any purpose, 60 to curve the blade, it is but necessary to increase the pressure of the grip on the handle portions bringing them close together as illustrated in Fig. 2. By releasing the pressure the blade immediately assumes its normal 65 straight position.

Having described my invention what I claim as new and desire to secure by Letters Patent, is:

A weeder formed of a single strip of elastic 70 metal, the central portion thereof being sharpened on both edges and constituting a blade, and the portions each side of the blade being bent to form vertical riser portions at right angles to the blade, inwardly extending portions 75 substantially parallel with the blade and upwardly extending parallel end portions forming a grip, the parallel portions of the grip being normally spaced apart and adapted to be drawn together when desired to curve 80 the blade, said blade being normally straight, substantially as described.

In testimony whereof I have signed my name to this specification in the presence of two subscribing witnesses.

JOHN C. WENNER.
